POWDER PUFF AND METHOD OF MAKING
THE SAME

Evangeline Burkhart, New York, N. Y.

Application January 27, 1934, Serial No. 708,595

3 Claims. (Cl. 132—78.5)

This invention relates to new and useful improvements in powder puffs and method of making same.

Powder puffs must be both inexpensive to produce, and free from rough edges which tend to irritate the skin. Heretofore to produce powder puffs at low cost and free from rough edges it has been the custom to stitch the cloth puff members in bag like form with the inside out, then to reverse the bag to expose the soft faces of the cloth puff members, then to pack the bag with wadding and to stitch up the "mouth" of the bag by hand to complete the powder puff. This method which has been employed for many years is expensive because of the time necessarily consumed in reversing the "bags", packing them, and hand stitching the "mouths" thereof. To machine stitch the cloth puff members together with the soft faces on the outside is open to objection. If the line of stitching is placed near the circumferential edges of the cloth puff members it will irritate the skin when the puff is used, and the stitching will soon break away from the circumferential edges and unravel. On the other hand if the line of stitching is placed in from the circumferential edges of the cloth puff members, it leaves free edges of material which makes the object unsatisfactory for use as a powder puff. Heretofore powder puffs when washed lost their shape and were unsatisfactory for further use.

The object of this invention is a powder puff which is as satisfactory when used as the powder puff of the prior art, and a method of manufacturing said puff which is less expensive than the method of the prior art.

Another object is a powder retaining powder puff.

Another object is a washable powder puff.

Another object is a sanitary powder puff display package.

Other objects will appear from the detailed description.

In the drawing comprising but a single sheet of eight figures numbered Figs. 1 to 8 inclusive; Fig. 1 is a front elevation of my improved form of powder puff.

Fig. 2 is a vertical cross-section thereof taken along line 2—2 of Fig. 1 looking in the direction of the arrows.

Fig. 3 is a front elevation of a modification.

Fig. 4 is a cross-section of the powder puff of Fig. 3 taken on line 4—4 of Fig. 3, looking in the direction of the arrows.

Fig. 5 is an enlarged detailed view showing the stitching.

Fig. 6 is a vertical cross-section of Fig. 5.

Fig. 7 is a front elevation of a commercial package showing a series of puffs; and

Fig. 8 is a perspective view showing the puff holding strip with one puff in place.

Like reference characters designate corresponding parts throughout the several figures of the drawing.

Referring to Figs. 1 and 2 the cloth puff members 11 and 12 may be of any suitable shape, but are preferably circular. The member 11 may be of any suitable fabric such as plush or puff-velour of which puffs are customarily made; the member 12 may be of the same fabric or may be made of blanket material, netting, or of any other form of fabric commonly used in the manufacture of powder puffs. The members 11 and 12 are placed back to back and an edging of chenille 13, or soft tubing or other similar soft material (skin non-irritant), is inserted between the adjacent faces of the members 11 and 12 so as to be partially exposed beyond the circumferential edges of the said members. The members 11 and 12 and the chenille 13 are now stitched together by means of a scallop stitch 14. The stitching 14 is not in a straight line but is zig-zag or sinuous, and draws in the members 11 and 12 at intervals as indicated at 23 (Fig. 5) to form a series of scallops 24 (Fig. 5). The chenille 13 is partially exposed being drawn down between the circumferential edges of the members 11 and 12 at intervals (between adjacent scallops 24) and is over-stitched at these points as at 25 to lock the chenille in place. The puff members 11 and 12 are so stitched as to define a peripheral guideway for holding the chenille 13 (see Fig. 6). The sinuous (zig-zag) line of stitching 14 is performed by machine. The scallop machine, shell machine, zig-zag machine or other suitable stitching machine can be used for this purpose.

As the material is not turned in as in the bag construction, no material is lost or wasted in this manner. The chenille 13 forms a very satisfactory edging because it is not only soft and therefore a non-irritant to the skin, but it also blends with the plush or puff-velour 11, and different color combinations produce many decorative effects. The scalloped edge 24 and chenille 13 also tend to hold the powder thus preventing it from falling off the edge of the puff to the floor.

To preserve the shape of the puff when washed, it may be quilt-stitched as at 18—18 (Figs. 3 and 4), thereby sub-dividing the puff into a plu-

rality of small cells thereby preventing the wadding 17 between the cloth puff members 15 and 16 from getting out of shape during washing. This makes it possible to wash the puff as often as desired and extends its useful life to the life of the cloth puff members 15 and 16.

It should be understood that one side (15) of the puff (Fig. 3) may be velour for smoothing down purposes, and the opposite side 16 may be 10 of blanket or net material to form a sifter or powder applicator. Different shapes may also be used if desired.

The puff may also be provided with a ribbon bow attachment 19 (Fig. 7). This ribbon is useful for holding the puff when in operation, as 15 well as decorative. A plurality of powder puffs 10 may be inserted in the opening 22 of a puff holding strip 21, as shown in Figs. 8 and 7. The puff unit thus formed is then readily inserted in 20 a suitable transparent or translucent envelope 20 of "cellophane" or the like and sealed to constitute a sanitary commercial package of two or 25 more powder puffs. The stitching 14 may be of the same color as the puff members 11 or 15 in which event it is hardly visible to the eye, or it may be made exceedingly decorative when used in contrasting colors. It should be understood however that no part of the stitching 14 will 30 contact the skin. The scallops also tend to mold themselves to the curves of the features facilitating the application and smoothing of the powder.

The wadding 17 may if preferred be quilt stitched to one of the cloth puff members only as for example 11 (Fig. 1) or 15 (Fig. 3). One manner of accomplishing this is to securely stitch the wadding 17 to one cloth puff member 15 only as for example the member 15 before stitching the cloth puff members 15 and 18 together by the 35 sinuous line of stitching 14—14.

What is claimed is:—

1. A powder puff having the puff members placed back to back, an edging of skin non-irritant material surrounding the peripheral edges of the puff members and positioned partially therebetween, and a sinuous line of stitching, passing through said puff-members and said edging and intersecting the circumferential edges of the puff members at equally spaced intervals to define a continuous series of scallops surrounding the edge of powder puff. 10

2. A powder puff having the puff members placed back to back, a wadding therebetween, an edging of skin non-irritant material surrounding the peripheral edges of the puff members and 15 positioned partially therebetween, and a sinuous line of stitching passing through said puff members and said edging and overlocking the edging and the circumferential edges of the puff members at equally spaced intervals to define a scalloped edge for said powder puff. 20

3. A washable powder puff having the puff members placed back to back, a wadding therebetween, an edging of skin non-irritant material surrounding the peripheral edges of the puff 25 members and positioned therebetween, a sinuous line of stitching passing through said puff members and said edging and overlocking the edging and the circumferential edges of the puff members at equally spaced intervals to define a scalloped edge for said powder puff, and lines of 30 stitches traversing the surface of said puff members and passing through said wadding to subdivide the puff into a plurality of wadded cells thereby defining a quilted puff. 35
